Atty.

UNITED STATES PATENT OFFICE.

THOMAS GREGORIE TULLOCH, OF LONDON, ENGLAND, ASSIGNOR, BY MESNE ASSIGNMENTS, TO AUTOMOTIVE GAS PRODUCER CORPORATION, A CORPORATION OF DELAWARE.

MEANS FOR ALTERING THE CLEARANCE IN INTERNAL-COMBUSTION ENGINES.

Application filed February 25, 1921. Serial No. 447,797.

To all whom it may concern:

Be it known that I, THOMAS GREGORIE TULLOCH, a subject of the King of Great Britain, residing at Bank Buildings, St. 5 James Street, in the county of London, England, have invented certain new and useful Improvements in or Relating to Means for Altering the Clearance in Internal-Combustion Engines, of which the following is a 10 specification.

This invention relates to means for altering the clearance in internal combustion engines which are adapted to use liquid fuel and has for its chief object to provide a device which enables existing engines of that 15 kind to be efficiently utilized for gaseous fuel, more particularly producer gas.

If an engine of the ordinary petrol type, such as that employed on motor vehicles, 20 is to serve for gaseous fuel it is desirable that the compression should be substantially increased, the compression of an ordinary petrol engine amounting to say, 60 to 85 lbs., while the compression desirable for gaseous 25 fuel would be about 120 to 140 lbs.

According to this invention, to adapt an engine constructed for use with liquid fuel for the utilization of gaseous fuel such as producer gas, I reduce the compression space 30 in the cylinder by any suitable method, such as doming the piston, and fit to the cylinder an auxiliary chamber adapted to be opened to or cut off from the compression space 35 of the cylinder. When the engine is running on gaseous fuel the auxiliary chamber is cut off and the reduced compression space is employed, so that the compression pressure is raised to the higher level desirable. Also on starting the engine it is desirable 40 that the compression pressure should be low and therefore the auxiliary chamber may then be opened to the cylinder and cut off when the engine has properly started. If liquid fuel is to be utilized the auxiliary 45 chamber is opened to the cylinder and allows of the reduced compression pressure found preferable.

In order that the said invention may be clearly understood and readily carried into

effect the same will now be more fully described with reference to the accompanying drawing which shows diagrammatically in elevation a cylinder provided with the auxiliary chamber in accordance with this invention.

A is the cylinder. B is the piston, the head of which is domed as shown at b. C is the auxiliary chamber mounted on the top or head of the cylinder and D is a valve or cock by which the chamber C may be connected up to the working space of the cylinder or cut off as required.

The auxiliary chamber C may, as shown, be in the form of a small cylinder secured on a stem c adapted to be screwed into a 65 tapped hole in the top a of the cylinder A, the stem carrying the valve or tap D with a lever or handle d or other operating device under the control of the driver, adapted to open the auxiliary chamber C to the 70 cylinder A on starting the engine and to cut it off when the higher compression pressure is required. A release tap c' is fitted to the chamber C, which enables the products of combustion in the chamber to escape 75 after closing the cock or valve D, and also provides means for allowing a detergent fluid to be inserted into the chamber so that when the products of combustion are permitted to escape, they will carry any deleterious 80 matter they may have collected in the chamber.

In altering an existing engine, for example, the engine of a motor lorry or other heavy motor vehicle, the ordinary pistons 85 are removed and replaced by a set of domed pistons such as is indicated at B in the diagram, or the cylinders may be lowered upon the crank case, or space reducing members may be fitted inside the cylinders to bring 90 the compression space down to the required volume. The auxiliary chamber C may be fitted in place of the existing compression tap or may be separately fitted to any convenient part of the upper end of the cylinder. All the valves controlling the communication between the auxiliary chambers and the cylinders of a multi-cylinder engine 95

may be interconnected so as to open or close at the same time.

What I claim and desire to secure by Letters Patent of the United States is:—

5 In an internal combustion engine, the combination with the cylinder thereof, a chamber adapted to be connected to or dis-

connected from the compression space in said cylinder so as to permit of different degrees of compression therein, and means 10 connected to said chamber to allow the products of combustion to escape therefrom.

THOMAS GREGORIE TULLOCH.
